UNITED STATES PATENT OFFICE.

CHARLES W. HURL, OF NANTY GLO, PENNSYLVANIA, ASSIGNOR TO MINERS SUPPLY AND EQUIPMENT COMPANY, OF JOHNSTOWN, PENNSYLVANIA, A COMMON LAW TRUST ESTATE.

MINE ALARM INSTRUMENT.

Application filed December 6, 1921. Serial No. 520,245.

To all whom it may concern:

Be it known that I, CHARLES W. HURL, a citizen of the United States, residing at Nanty Glo, in the county of Cambria and 5 State of Pennsylvania, have invented certain new and useful Improvements in Mine Alarm Instruments, of which the following is a specification.

This invention relates to alarm devices for 10 giving warning of the threatened collapse of a wall or roof, especially in mines and similar locations, and has for one of its objects to improve and simplify the construction and increase the efficiency of devices of this 15 character.

Another object of the invention is to provide a device of this character which is self contained and which can be readily transported with the mining tools and other portable objects or material employed in mining 20 and like operations.

With these and other objects in view, the invention consists in certain novel features of construction as hereinafter pointed out in 25 the claims, and in the drawings illustrative of the preferred embodiment of the invention;—

Figure 1 is a side elevation of the improved device, viewed from one side.

30 Fig. 2 is a similar view from the opposite side.

Fig. 3 is a transverse section taken on the line 3—3 of Fig. 2.

Fig. 4 is a transverse section taken on the 35 line 4—4 of Fig. 2.

Fig. 5 is an enlarged detail illustrating the construction of the longitudinally adjustable standard.

The improved device includes a standard 40 formed of coacting portions 10 and 11, "halved" for portions of their lengths as shown at 12 and 14 with the portion 13 longitudinally slotted as shown at 14 and the portion 12 provided with a clamp bolt 45 15 extending through the slot, the bolt having a wing nut 16. By this means the standard portion may be adjusted longitudinally within the range of the slot 14.

Attached to the opposite faces of the 50 standard portion 11 and its "halved" portion 13 are guide plates 17 and 18, the plates having guide flanges 19 and 20 extending over the adjacent "halved" part 12 of the standard portion 10. A clip device 21 is attached at its ends to the "halved" portion

13 and extends around the plates 17 and 18 and their flanges 19 and 20, as shown.

The standard portion 11 is provided with laterally directed leg members 22, to hold the improved device in vertical position. 60

Attached at 23 to the upper end of the standard portion 10 is a laterally extending curved arm 24 carrying a signal gong of approved construction and represented at 24, the gong device including a tapper for 65 sending element therefor, as indicated at 26 and which extends from one side.

Pivoted at 27 to the member 10, preferably at the side opposite to the arm 24, is a bell crank lever including leg portions 28 70 and 29.

The leg 28 is longer than the leg 29, and said leg 28 extends to a position whereby it will oppose the tapper or sounding element 26 of the gong. The leg 29 is directed vertically and has its upper portion threaded, as is indicated at 30.

A pressure operated member 31, substantially in the form of a turn buckle, has one end threaded for engagement with the 80 threaded portion 30, of the arm 29 of the bell crank lever. It is the lower end of the pressure operated member 31, which has such engagement with the leg 29 of the bell crank lever. The upper end of the pressure operated member 31, has extending therefrom a spur 32.

The improved device is to be used where the roof or roof supports are liable to be crushed, for instance in mines, tunnels and 90 like localities, and in installing the improved device the miner sets the branching leg portions 22 upon the floor indicated at 33 and adjusts the standard members and the point or spur 32 against the roof, indicated at 95 34, until the terminal 35 of the leg 28 of the bell crank lever is relatively close to the tapper or sounding element 26.

In making these adjustments, a certain strain is applied to the device to hold it in 100 position.

So long as the conditions are normal, the device will remain in inoperative position and the gong kept from sounding.

If the roof starts to sag or collapse, the 105 arm 29 will be depressed and elevate the toe end 33 of the bell crank lever and actuate the tapper or sounding element and cause the gong to sound, thus notifying the miners that the roof is settling and giving 110

them time to escape and carry their tools and other objects with them.

The device is simple in construction, certain in action, and can be located wherever devices of this character are required.

The preferred embodiment of the invention is disclosed in the drawings and set forth in the specification, but it will be understood that any modifications within the scope of the claims may be made in the construction without departing from the principle of the invention or sacrificing any of its advantages.

Having thus described the invention, what is claimed as new is:—

1. A device for the purpose set forth comprising an adjustable standard, a shiftable bell crank lever pivoted to the upper end thereof and including a vertical and a horizontal arm, the latter being of greater length than the former; a sounding element actuated by and arranged in proximity to the free terminus of the horizontal arm of said lever; and a vertically adjustable pressure operated member carried by the vertical arm of said lever and adapted when pressure is applied thereto to shift said lever causing the horizontal arm thereof to engage and operate said sounding element.

2. A device for the purpose set forth comprising a standard, a shiftable bell crank lever pivoted to said standard and including a vertical and horizontal arm, a sounding element operated by and positioned in proximity to the free terminal portion of the horizontal arm of said lever, and a pressure operated member carried by the vertical arm of said lever and adapted when pressure is applied thereto to shift said lever causing thereby the horizontal arm thereof to engage and operate said sounding element.

3. A device for the purpose set forth comprising a standard, a laterally disposed arm carried thereby, a sounding element secured to said arm, a bell crank lever pivoted to said standard and including a ver-

tical and a horizontally disposed arm, said horizontally disposed arm sufficient in proximity to and adapted when shifted to actuate said sounding element, and a pressure exerting member carried by the vertical arm of said lever and adapted when pressure is applied thereto to shift said lever causing thereby the operation of the sounding element by the horizontal arm of the lever.

4. A device for the purpose set forth comprising a standard, a laterally disposed arm carried thereby, a sounding element secured to said arm, a bell crank lever pivoted to said standard and including a vertical and a horizontally disposed arm, said horizontally disposed arm sufficient in proximity to and adapted when shifted to actuate said sounding element, a pressure exerting member carried by the vertical arm of said lever and adapted when pressure is applied thereto to shift said lever causing thereby the operation of the sounding element by the horizontal arm of the lever, and means to provide for the adjusting of said pressure operated element.

5. A device for the purpose set forth comprising a standard, a laterally disposed arm carried thereby, a sounding element secured to said arm, a bell crank lever pivoted to said standard and including a vertical and a horizontally disposed arm, said horizontally disposed arm sufficient in proximity to and adapted when shifted to actuate said sounding element, a pressure exerting member carried by the vertical arm of said lever and adapted when pressure is applied thereto to shift said lever causing thereby the operation of the sounding element by the horizontal arm of the lever, means to provide for the adjusting of said pressure operated element, and means to provide for adjusting the length of said standard.

In testimony whereof, I affix my signature hereto.

CHARLES W. HURL.
